L. ARKIN.
FASTENER.

APPLICATION FILED JAN. 28, 1918.

1,284,038.

Patented Nov. 5, 1918.

Inventor:
Louis Arkin,
by Frank Robert Cusack,
his Attorney.

UNITED STATES PATENT OFFICE.

LOUIS ARKIN, OF BOSTON, MASSACHUSETTS.

FASTENER.

1,284,038.

Specification of Letters Patent.

Patented Nov. 5, 1918.

Application filed January 28, 1918. Serial No. 214,072.

To all whom it may concern:

Be it known that I, LOUIS ARKIN, a citizen of the United States of America, and resident of Boston, in the county of Suffolk and State of Massachusetts, have invented new and useful Improvements in Fasteners, of which the following is a specification.

This invention relates to separable fasteners of the general type comprising complementary stud and socket members commonly used as fastening means for garments, gloves, automobile curtains and like purposes. The fasteners of this general type heretofore provided, other than those of the so-called "sew-on" type, are for the most part adapted and intended to be permanently secured to the material with the result that they are very difficult of removal when, as not infrequently happens, it becomes necessary or desirable to remove the fastener or change its position upon the material. Furthermore, special tools and appliances are required for affixing these fasteners to the material and such tools and appliances are not commonly possessed by, or readily available to, many persons who have occasion to affix fasteners to material.

It is the object of this invention to provide fastener members of this general class which can be secured to the material without the employment of special tools or appliances and which can be readily removed from the material when such removal becomes for any reason necessary or desirable, thus providing a fastener adapted for general use by all classes of users.

Referring to the drawings which illustrate certain embodiments of the invention,—

Figure 1 is a side view of a socket member with its retaining plate embodying the invention;

Fig. 2 is a bottom plan view of the socket member shown in Fig. 1;

Fig. 3 is a bottom plan view of the retaining plate shown in Fig. 1;

Fig. 4 is a horizontal section, partly in elevation, of the members shown in Figs. 1 and 3 secured to material;

Fig. 5 is a bottom plan view of the fastener members shown in Fig. 4;

Fig. 6 is a side view of a stud member with its retaining plate embodying the invention;

Fig. 7 is a bottom plan view of the fastener member shown in Fig. 6;

Fig. 8 is a longitudinal section partly in

elevation of the fastener member shown in Fig. 6 showing the parts affixed to material; and

Fig. 9 is a bottom plan view of the fastener member shown in Fig. 8.

The fastener member shown in Figs. 1 to 5 inclusive is of usual contour and comprises a dome or casing A and a base plate A' having the usual stud-receiving opening. While I prefer the particular socket member shown having the stud-retaining and releasing means within the casing A shown in my copending application for patent Ser. No. 176,820, it will be understood that the particular stud-retaining and releasing means within the casing are not essential to the present invention and that the socket may be provided with any desired stud-retaining means.

The base plate A' is provided with a downwardly extending annular skirt A² which surrounds the stud-receiving opening and is preferably formed integral with said plate. Said skirt has at its bottom edge a plurality of upwardly turned ears A³ oppositely disposed as shown and forming an elongated locking head.

B is the socket holding plate adapted to be disposed upon the opposite side of the material from the socket member proper. It is provided with a central elongated opening B' preferably of oval contour through which the skirt A² with its locking head formed by the ears A³ can freely pass when in one position only so that when said skirt A² is passed through said holding plate the parts can be locked by relative rotary movement thereof as presently to be described. At the side of said opening B' the plate B is provided with oppositely disposed slots B² adapted to retain the edges of the ears A³.

In securing the socket member to material, the member proper and the retaining plate B are disposed on opposite sides of the material and the skirt A² with its ears A³ is passed through the material into and completely through the opening B' of the plate B. The socket and plate are then relatively rotated 90° from the position shown in Fig. 1 to the position shown in Figs. 4 and 5, whereupon the ears A³ forming the locking head are moved to a position transverse of the opening B' so that the parts are locked and yieldingly held in locked relation by entrance of the edges of the ears A³ into the slots B².

To remove the socket member, the member proper and its retaining plate B are pressed toward each other until the edges of the ears A³ leave the slots B², permitting relative rotation of the plate and socket member to a position 90° from locked position, the skirt A² with its locking head being then free to pass out of the opening B'.

Referring now to the stud member shown 10 in Figs. 6 to 9 inclusive, the stud S is of usual contour and construction and has the usual flange S'. The portion of the stud below the flange S' is provided with a flattened elongated locking head S² formed integral 15 with said stud and preferably provided on its top face with a pair of oppositely disposed sockets C.

The stud holding plate P, which is adapted to be disposed upon the side of the material opposite to the stud S, has a central elongated opening P' preferably of the shape shown, through which the locking head S² of the stud can pass in one position only, so that when said head S² is 20 passed through said plate the parts can be locked by relative rotary movement thereof. Preferably said plate P has a pair of oppositely disposed projections or bosses D which coöperate with the sockets C provided 25 in the locking head S².

In securing the stud member to material the stud S and retaining plate P are disposed on opposite sides of the material and the locking head S² is passed into and completely through the opening P' of the holding plate. The stud and plate are then relatively rotated 90° from the position shown in Fig. 6 to the position shown in Figs. 8 and 9, whereupon the locking head is moved 30 to a position transverse of the opening P' so that the parts are locked and yieldingly held in locked relation by entrance of the projections D into the sockets C.

To remove the stud member, the stud S 45 and its retaining plate P are pressed toward each other until the projections D are free to leave their sockets C permitting relative rotation of the stud and plate to a position 90° from locking position, whereupon the locking head S² is free to pass out 50 of the retaining plate.

Preferably the socket retaining plate B is provided with an annular ridge B³ of substantially the height of the ears A³ when in 55 locked position as shown in Fig. 4 so that the bottom of said retaining plate presents a substantially smooth surface. The said retaining plate P has a similar flange P².

It will, I believe, be clear that a fastener 60 member made in accordance with my invention as above described can be readily affixed to material by persons without experience in the particular work, and without the employment of special tools. It will 65 also be apparent that the fastener can be

readily removed from the material as occasion may require.

I claim:

1. A fastener member comprising two parts adapted to be disposed on opposite 70 sides of material, one of said parts having a single, central opening and the other of said parts having a locking head adapted to be passed through said opening and thereafter to be turned transverse thereof and to 75 engage the outer face of said first named part to lock said parts in operative position.

2. A fastener member comprising two parts adapted to be disposed on opposite 80 sides of material, one of said parts having a single, central opening and the other of said parts having a locking head adapted to be passed through said opening and thereafter to be turned transverse thereof and to 85 engage the outer face of said first named part to lock said parts in operative position, and means yieldingly to retain said parts in locked relation.

3. A fastener member comprising two 90 parts adapted to be disposed on opposite sides of material, one of said parts having an opening and the other of said parts having a depending annular skirt provided with a locking head, said head adapted to 95 be passed through said opening and thereafter to be turned transverse thereof to lock said parts in operative position.

4. A fastener member comprising two parts adapted to be disposed on opposite 100 sides of material, one of said parts having an opening and the other of said parts having a depending annular skirt provided with a locking head, said head adapted to be passed through said opening and thereafter to be turned transverse thereof to lock 105 said parts in operative position, and means yieldingly to retain said head in locked relation.

5. A fastener member comprising two 110 parts adapted to be disposed on opposite sides of material, one of said parts having an opening and the other of said parts having a depending annular skirt provided on its bottom edge with a plurality of upturned ears forming a locking head, said ears adapted to be passed through said opening and thereafter to be turned transverse thereof to lock 115 said parts in operative position.

6. A fastener member comprising two parts adapted to be disposed on opposite sides of material, one of said parts having an elongated opening and a plurality of 120 slots, and the other of said parts having a 125 depending annular skirt provided on its bottom edge with a plurality of upturned ears forming a locking head, said head adapted to be passed through said opening and thereafter to be turned transverse of 130

said opening to lock said parts in operative position and said ears adapted to enter said slots yieldingly to retain said ears in locked relation.

- 5 7. A fastener member comprising two parts adapted to be disposed on opposite sides of material, one of said parts having an elongated opening and a pair of oppositely disposed slots, and the other of said parts having a depending annular skirt provided on its bottom edge with a pair of

oppositely disposed upturned ears forming an elongated head, said head adapted to be passed through said opening and thereafter to be turned transverse of said opening to lock said parts in operative position, and said ears adapted to enter said slots yieldingly to retain said head in locked relation. 15

Signed by me at Boston, Massachusetts, 20 this nineteenth day of January, 1918.

LOUIS ARKIN.
